UNITED STATES PATENT OFFICE

2,592,037

SPRING-ACTUATED STUD WRENCH

John Keiser, Windsor, Colo.

Application June 6, 1949, Serial No. 97,447

3 Claims. (Cl. 81—53)

1

This invention relates to a socket wrench for stud bolts, and has for its principal object the provision of a small, light-weight, highly efficient socket wrench which can be slipped over a threaded stud bolt for screwing the latter into place, or for unscrewing it from place.

The invention is particularly adaptable for removing tight engine head stud bolts which become rusted and corroded in place and are difficult to remove. Another object of the invention is to provide a stud bolt wrench which will handle a variety of stud bolt sizes, and which will automatically ratchet in either desired direction against the stud bolt so that only a short turning arc is required.

Other objects and advantages reside in the detail construction of the invention, which is designed for simplicity, economy, and efficiency. These will become more apparent from the following description.

In the following detailed description of the invention, reference is had to the accompanying drawing which forms a part hereof. Like numerals refer to like parts in all views of the drawing and throughout the description.

In the drawing:

Fig. 1 is a side view of the improved stud bolt wrench;

Fig. 2 is a top view thereof;

Fig. 3 is a horizontal cross-section, taken on the line 3—3, Fig. 1;

Fig. 4 is a vertical cross-section, taken on the line 4—4, Fig. 2;

Figs. 5 and 6 are horizontal cross-sections, taken on the lines 5—5 and 6—6, respectively, Fig. 4; and

Fig. 7 is a bottom view thereof.

In Fig. 5 the wrench is illustrated in the empty position and in Fig. 6 it is illustrated with a typical stud bolt 34 in place therein.

The improved wrench employs a cup-like case 10 having a circular stud opening 11 in its bottom for the passage of the stud bolt 34, and having a normally open top closed by means of a top plate 12.

Three pivot openings 13 are equally spaced and surround the stud opening 11. Each of the pivot openings 13 receives a pivot lug 14 formed on the lower outer extremity of a swinging dog 15 and projecting downwardly therefrom.

The dogs have a semi-pointed, free extremity, from which two arcuate, ratchet-notched faces 16 extend. These free extremities pivot about the axis of the lugs 14. The pivoted extremities of the dogs are rounded and set into receiving

2

grooves 17 in the inner wall of the case 10. The thrust reaction of the dogs 15 is received by the grooves 17.

A circular boss 18 arises from each of the dogs 15 adjacent its free extremity. The three bosses 18 are received in radial slots 19 formed in a slotted plate 20. A center opening 21 is also formed in the plate 20 and corresponds in diameter and position to the bottom opening 11.

10 It can be seen that when the plate 20 is rotated in one direction, the dogs 15 will be swung simultaneously to the right, and when rotated in the other direction, will be swung simultaneously to the left. When the axes of the slots 19 are parallel to the axes of the dogs 15, the latter will be in their closed or radial positions, with their extremities closely approaching each other, as shown in Figs. 2 and 5.

The plate 20 is constantly urged to this closed 20 or radial position by means of two compression springs 22, which act against opposite sides of a vertical crank pin 23, which is affixed in and arises from the slotted plate 20. The springs 22 are contained in a circumferential notch 24 formed in the edge of a stationary flange 25.

25 Keys 26 project from the flange 25 into key notches 27 in the opposite sides of the case 10 so as to prevent rotation of the flange within the case. A hollow stem 28 is concentrically secured to the flange 25 and projects upwardly therefrom, terminating at its upper extremity in wrench-engaging faces 29.

30 A split retaining ring 30 is inset in an annular groove in the inner wall of the casing 10 to hold the flange 25 downwardly therein. A knurled operating sleeve 31 rotatably surrounds the stem 28 and extends downwardly through the top cap 12 so as to rest upon the flange 25.

The sleeve 31 carries a bifurcated ear 32 extending outwardly from its lower extremity below the cap 12. The pin 23 is received in the bifurcated ear 32. The cap 12 is held in place by means of cap screws 33 which are threaded into the flange 25.

45 If it is desired to turn the stud 34 to the right, the sleeve 31 is rotated to the right to swing the dogs outwardly to the position of Fig. 6 with relation to the stud 34. A wrench of any desired type is then placed on the wrench faces 29 and 50 the stem 28 rotated back and forth. At each movement to the right, the teeth of the faces 16 will bite into the stud to rotate the latter to the right. When the stem 28 is reversed, the teeth will slide over the surface of the stud to obtain 55 a new grip thereon.

To unscrew the stud or turn it to the left, the dogs 15 are swung to the left by rotating the sleeve 31 before being placed on the stud so that the opposite faces 16 will engage the stud to ratchet thereon to unscrew the latter from position.

While a specific form of the improvement has been described and illustrated herein, it is to be understood that the same may be varied, within the scope of the appended claims, without departing from the spirit of the invention.

Having thus described the invention, what is claimed and desired secured by Letters Patent is:

1. A stud bolt wrench comprising: a cup-like case having a stud-receiving opening in its bottom and an open top, there being three pivot openings in the bottom of said case equally spaced about the central stud opening; three, pointed, toothed dogs positioned normally in a radial position within said casing; a pivot boss extending downwardly from the outer extremity of each dog into one of said pivot openings; a projecting lug extending upwardly from each dog adjacent its axial extremity; a slotted plate positioned in said case above said dogs, said plate being provided with a central stud-receiving opening, and with radially extending slots each slidably receiving one of said bosses; means for rotating said case; an axially positioned, hollow stem arising from said case; a circular flange formed on the lower extremity of said stem within said case and positioned against said slotted plate; means for preventing said flange from rotating within said case; a rotatable sleeve surrounding said stem and extending into said case; and means on said sleeve for rotating said slotted plate in either desired direction.

2. A stud bolt wrench comprising: a cup-like case having a stud-receiving opening in its bottom and an open top, there being three pivot openings in the bottom of said case equally spaced about the central stud opening; three, pointed, toothed dogs positioned normally in a radial position within said casing; a pivot boss extending downwardly from the outer extremity of each dog into one of said pivot openings; a projecting lug extending upwardly from each dog adjacent its axial extremity; a slotted plate positioned in said case above said dogs, said plate being provided with a central stud-receiving opening, and with radially extending slots each slidably receiving one of said bosses; means for rotating said case; an axially positioned, hollow stem arising from said case; a circular flange formed on the lower extremity of said stem within said case and positioned against said slotted plate; means for preventing said flange from rotating within said case; a rotatable sleeve surrounding said stem and extending into said case; and means on said sleeve for rotating said slotted plate in either desired direction.

tating within said case; a rotatable sleeve surrounding said stem and extending into said case; a bifurcated ear projecting from said sleeve within said case over said flange; and a pin fixed in said slotted disc and extending into said bifurcated ear to transmit the movements of said sleeve to said slotted plate.

3. A stud bolt wrench comprising: a cup-like case having a stud-receiving opening in its bottom and an open top, there being three pivot openings in the bottom of said case equally spaced about the central stud opening; three, pointed, toothed dogs positioned normally in a radial position within said casing; a pivot boss extending downwardly from the outer extremity of each dog into one of said pivot openings; a projecting lug extending upwardly from each dog adjacent its axial extremity; a slotted plate positioned in said case above said dogs, said plate being provided with a central stud-receiving opening, and with radially extending slots each slidably receiving one of said bosses; means for rotating said case; an axially positioned, hollow stem arising from said case; a circular flange formed on the lower extremity of said stem within said case and positioned against said slotted plate; means for preventing said flange from rotating within said case; a rotatable sleeve surrounding said stem and extending into said case; a bifurcated ear projecting from said sleeve within said case over said flange; and a pin fixed in said slotted disc and extending into said bifurcated ear to transmit the movements of said sleeve to said slotted plate; an expanding ring resting in an internal notch in said case and acting to maintain said flange in place therein; and a cover plate closing the top of said case about said sleeve.
